(57) **CLAIM**

The ornamental design for a toy car, as shown and described.

DESCRIPTION

FIG. 1 is a front view of a toy car showing the new design.
FIG. 2 is a rear view thereof.

FIG. 3 is a left side view thereof.

FIG. 4 is a right side view thereof.

FIG. 5 is a top view thereof; and,

FIG. 6 is a bottom view thereof.

The broken lines in the Figures show portions of the toy car that form no part of the claimed design.

1 Claim, 6 Drawing Sheets
